UNITED STATES PATENT OFFICE.

DAVIE ALLEN GRAY, OF CHATTANOOGA, TENNESSEE.

POST-HOLE DIGGER.

No. 853,010.

Specification of Letters Patent.

Patented May 7, 1907.

Application filed October 27, 1906. Serial No. 340,846.

To all whom it may concern:

Be it known that I, DAVIE ALLEN GRAY, a citizen of the United States, and a resident of Chattanooga, in the county of Hamilton and State of Tennessee, have invented certain new and useful Improvements in Post-Hole Diggers, of which the following is a specification.

My invention is an improvement in digging apparatus, especially designed for use in digging post holes; and the invention consists in certain novel constructions and combinations of parts as will be hereinafter described and claimed.

In the drawings Figure 1 is a perspective view of a machine embodying my invention. Fig. 2 is a vertical longitudinal section thereof, parts being broken away. Fig. 3 is a detail perspective view of the cutter, Fig. 3^a is a bottom plan view thereof, and Fig. 4 shows a somewhat different form of cutter from that shown in Fig. 3. Fig. 5 is a detail cross section showing the clamping band of the casing.

In carrying out my invention I employ a barrel or casing A open at its lower end and provided at its upper end with a removable cap B and below the same with a lateral discharge opening A' and spout A² leading therefrom.

The cap B is fitted on the upper end of the barrel A and secured by bolts B' and the top plate B² of the cap B has a central opening through which the main shaft C projects. This top plate B² is made comparatively thick and the shaft C has its upper section connected at its lower end with the upper end of the lower section preferably by screw coupling, as shown in Fig. 2, within the top plate B², so the said top plate will brace the coupling between the upper and lower sections of the main shaft, the casing A and the main shaft being preserved in such relation by the devices at the lower end of the barrel A which will now be described.

At the lower end the barrel A is provided with a base ring a whose outer side is flush with that of the body of the barrel A and whose inner diameter is slightly less than the inner diameter of the barrel A so that the auger flights D on the lower section C' of the main shaft fit at their lower ends within the base ring and will be spaced above the base ring slightly apart from the inner surface of the barrel A in the operation of the machine, thus avoiding friction between the auger and

the body of the barrel throughout the length of the latter. The base ring is provided with a cross-bar a' in which journals the stem C² at the lower end of the section C' of the main shaft. This stem C² projects below the crossbar a' and the cutter E is secured on such extension of the stem C² by a clamping screw E². This cutter E being held below the cross-bar a' and the auger flights bearing above the said crossbar operate to prevent independent endwise movement of the main shaft, and the casing A and so preserve the parts in relation to each other with the coupling between the sections of the main shaft within the opening in the top plate of the cap B, as best shown in Fig. 2 of the drawings.

The cutter E on the lower end of the main shaft and below the bar a' has its main or body portion E' fitting within the lower end of the base ring a and has at its lower end which projects below the base ring a the lateral projections or wings E² which project below the base ring and bear against the lower edge thereof as the cutter is revolved by the devices presently described. This cutter may be a single cutter as shown in Fig. 4, but is preferably a double cutter, as shown in Figs. 3 and 3^a, the latter having the cutting edges e which incline upwardly to direct the cut material into the base ring a of the barrel and it will be fed up the barrel by the auger and delivered out of the spout A², as will be understood from Figs. 1 and 2 of the drawings. As shown in Figs. 3 and 3^a the cutting portion e of the cutter projects beyond the upright faces of the body portion E' and aids in directing the cut material up into the body of the casing. The base ring a is important as it takes the wear and can be readily removed whenever desired besides forming an offset within the barrel to relieve the flights of the auger from frictional contact with the body of the casing in the operation of the invention.

The barrel or casing A is provided near its upper end with a sectional clamping band F whose sections are hinged together at F' at the front of the casing and are connected in rear of the casing by means of a bolt F², as best shown in Fig. 5 of the drawings. The clamping band F has a dropped portion f fitting down below the spout A² and this band is provided on its opposite sides with projecting lugs F³ having vertical openings for the guide rods G along which the barrel A

slides in the operation of the machine. These guide rods G are supported from the top frame H, shown in Fig. 1, and which will now be described. This top frame has the side bars H' which are connected by the crossbar H² and on these side bars are mounted the stands H³ connected by the top bar H⁴, and one of these stands H³ is provided with bearings H⁵ for the drive shaft I which may be driven by a crank handle I' or in any other suitable manner and is provided with a bevel gear I² meshing with a bevel pinion I³ on the main shaft C. The main shaft C has a groove or key-way I⁴ and the pinion I³ has a key I⁵ fitting in said groove I⁴ so the main shaft may slide freely through the pinion I³ and yet will be turned thereby in the operation of the machine. The main shaft is journaled in the crossbar H² of the top frame and also in the top bar H⁴ of said frame and is movable freely in a longitudinal direction through both said bearings being held thereby in vertical position in the operation of the machine, as will be understood from Fig. 1 of the drawings. The said bars H' of the top frame are connected at their ends by bars h which brace and give steadiness to the top frame at its corners, as is desired.

The top frame H is mounted on legs or uprights J which are passed at their upper ends through openings in the top frame so they may be adjusted longitudinally therein and secured in any suitable adjustment by clamping screws h'. These legs J of which I use two at each side of the machine, are adapted at their lower ends to bear on the ground and form supports for connecting rods K one at each side of the machine and bearing between their ends and between their respective legs J guide blocks L which may be adjusted along their respective connecting rods K and secured in any suitable adjustment by clamping screws L' and are provided with upright openings L² for the guide rods G of the casing A. The connecting rods K may be adjusted vertically along their supporting legs J and secured in any suitable adjustment. To this end I provide on the legs J joint blocks M through which the legs J pass so the blocks may be adjusted up and down on the legs and secured in any suitable adjustment by clamping screws M' and these joint blocks M are provided with lateral openings M² through which the connecting rods K pass and are secured by the clamping screws M³, as will be understood from Fig. 1. From this figure it will be noticed the connecting rods with their blocks L may be adjusted up and down on the legs J and held in any suitable adjustment whereby to secure the guide blocks L in position for abutment by the lugs G of the casing A to limit the downward movement of the said casing, and thus form a gage by which to regulate the depth of the holes dug by the

machine in the use thereof. It will be understood that the guide rods G may be graduated or otherwise marked to indicate feet or other measures so the depth of the holes may be readily regulated as desired. Springs N bear between the lugs F and the top frame and give a downward tension to the casing in the use of the machine.

In operation the connecting rods K being preferably set to regulate the depth of the cut as desired, the drive shaft may be turned, thus operating to turn the cutter to form a hole of the desired depth. The lugs F³ are provided with clamping screws F⁴ so that when desired the casing may be held up on the main shaft with the springs N under tension.

I claim:

1. The combination substantially as herein described of the top frame having vertical bearings for a main shaft, legs, means for securing the upper ends of the legs adjustably to the top frame, connecting rods extending between the legs at the opposite sides of the machine, means for adjustably connecting the said connecting rods with their respective legs, guide blocks on the connecting rods and having openings for upright guide rods, upright guide rods in said openings and extending between the blocks and the top frame, springs on said guide rods; a main shaft journaled in and movable vertically within the top frame, gearing in the top frame for driving said shaft, said main shaft being composed of upper and lower sections, a casing encircling the lower end of the main shaft and having a cap provided with a top plate within which the coupling between the upper and lower sections of the main shaft is fitted, a base ring at the lower end of the main shaft and having a crossbar, flights on the lower section of the main shaft bearing above said crossbar, a cutter on the main shaft below the said crossbar, said flights and the cutter operating to prevent independent endwise movement of the main shaft and casing, and a clamping band on the casing and having lateral lugs fitting on the guide rods below the springs thereon, all substantially as and for the purpose set forth.

2. The combination in a machine substantially as described of a top frame, a main shaft journaled therein, gearing within the main top frame for driving the main shaft, said shaft being provided at its lower end with a cutter and above the same with conveyer flights for lifting the cut material, a casing encircling the lower portion of the main shaft and movable longitudinally therewith, guide rods connected with the top frame and along which the casing is movable longitudinally, springs for giving a downward pressure to the casing, legs connected with the top frame and connecting rods between the legs at the opposite side of the ma-

chine and having means for limiting the downward movement of the casing, substantially as set forth.

3. A machine substantially as described having a main shaft, a casing encircling the same, a base ring at the lower end of the casing and having a crossbar, a main shaft having conveyer flights above the crossbar, and a cutter on the main shaft below the crossbar and having lateral extensions or wings underlying the base ring, and means for operating the main shaft, substantially as set forth.

4. The combination of a casing, a cap fitting and secured on the upper end thereof and having a top plate provided with an opening for a main shaft, the casing having a lateral spout below the said cap, a main shaft having upper and lower sections coupled within the opening in the top plate of the cap, a cutter at the lower end of the main shaft, and flights on said shaft above the said cutter and within the casing, and means for operating the main shaft, substantially as set forth.

5. The combination of a top frame, legs for supporting said frame and adjustably connected therewith, a main shaft journaled in and movable vertically within the top frame and having at its lower end a cutter, and a conveyer flight above the same, a barrel or casing encircling the lower end of the main shaft and movable vertically therewith, means for operating the main shaft, guide devices for the barrel or casing whereby the same may be moved vertically and be held from turning, and means supported on the legs for limiting the longitudinal movement

of the barrel or casing, substantially as described.

6. The combination of a top frame, legs for supporting the same, a main shaft movable vertically within the top frame and having a cutter at its lower end, a barrel or casing encircling the lower portion of the main shaft and movable longitudinally therewith, connecting rods between the legs at the same side of the machine and limiting the longitudinal movement of the barrel or casing, and means for securing the said connecting rods in different positions along their respective legs, substantially as set forth.

7. The combination with the top frame and its legs, of a main shaft, a barrel or casing encircling the main shaft and movable longitudinally therewith, connecting rods between the legs at the same side of the machine, joint blocks adjustable vertically along the legs and having lateral openings within which the connecting rods are secured and clamping screws for securing said blocks to the legs and to the connecting rods, substantially as set forth.

8. The combination with the casing and its base ring having a crossbar, of a main shaft extending through the crossbar, a cutter on the main shaft below the crossbar, and conveyer flights on the main shaft above the crossbar, and means for operating the main shaft, substantially as set forth.
